Primary Examiner — Bridget L Eland(74) *Attorney, Agent, or Firm* — Muncy, Geissler, Olds & Lowe, P.C.(57) **CLAIM**

The ornamental design for a handle for medical instrument, as shown and described.

DESCRIPTION

FIG. 1 is a left side elevational view of the handle for medical instrument of the present invention.

FIG. 2 is a right side elevational view of the handle for medical instrument of FIG. 1.

FIG. 3 is a front perspective view of the handle for medical instrument of FIG. 1.

FIG. 4 is a rear perspective view of the handle for medical instrument of FIG. 1.

FIG. 5 is a top perspective view of the handle for medical instrument of FIG. 1

FIG. 6 is a bottom plan view of the handle for medical instrument of FIG. 1; and,

FIG. 7 is a three-quarter view of the handle for medical instrument of FIG. 1.

The broken lines shown in the views are included for the purpose of illustrating portions of the handle for medical instrument that form no part of the claimed design.
